UNITED STATES PATENT OFFICE

FRANK N. MARIANI, OF NEW YORK, N. Y.

FEATHERWEIGHT PIPE

Application filed May 22, 1931. Serial No. 539,325.

The present invention relates broadly to improvements in a pipe construction and more particularly to means for conducting and radiating excessive heat originating within the bowl of a metal pipe of light weight.

Hitherto metal pipe bowls were partially provided with an increased radiating surface in the form of spatially arranged annular fins. The purpose of the fins was to drive off the heat from the outer surfaces of the bowl transmitted from the inside by conduction. In actual practice, however, it has been found that such a construction although radiating some heat failed to provide a cool smoke with the result that hot fumes would be conducted through the pipe stem to the user.

To overcome this disadvantage the stem 20 of the pipe was provided with a plurality of fins to increase the surface radiating characteristics thereof and even with this supplemental radiating surface of the pipe, if used, did not produce a cool smoke.

Accordingly, one of the objects of the present invention resides in the provision of means for producing a cool smoke with a metal pipe without any deleterious effects to the user.

Specifically, another object is to provide a metal pipe of light weight having the bowl, the stem and the portion of the stem providing a seat for the bowl each constituted with supplementary radiating means.

Still another aspect of the invention and an advantage thereof contemplates means to radiate and disperse heat from the hottest part of the bowl.

A further aspect is to provide a pipe bowl 40 with closely spaced fins or ribs extending exclusively the entire height thereof and a stem for supporting the bowl with closely spaced fins or ribs extending substantially the entire length thereof.

How all the above features of my invention are carried into effect will be best understood from the following specific description in detail of a preferred embodiment and although such preferred embodiment is explained merely as illustrative of the inven-

tion and is not considered a limitation thereon, the invention will be best understood from a consideration of such specific procedure. To aid the following specific description of the construction and principles of my invention, I refer to the accompanying drawing in which.

Fig. 1 is a side view in elevation of my improved pipe construction.

Fig. 2 is a front view thereof.

Fig. 3 is a sectional view taken along the line 3—3, Fig. 2 in the direction of the arrows.

Fig. 4 is a longitudinal sectional view along the line 4—4, Fig. 3 in the direction of the arrows.

As illustrated 10 broadly designates a pipe bowl, preferably of metal, and of a light weight material, such as aluminum. The bowl 10 contains the pocket 11 in which tobacco may be properly packed. Integrally associated with the body of the bowl are a plurality of ribs or fins 12 in closely spaced relation and extending substantially the entire height of the bowl and along the outer surface, to increase the heat radiating capacity thereof. It is to be understood, of course, that instead of providing fins or ribs as illustrated, the bowl may include any other suitable corrugated surfaces to increase its radiating capacity as is well understood.

Depending from the bottom wall 13 of the bowl and preferably cast integral therewith is the tube or neck portion 14 provided with the axially disposed bore or channel 15 which communicates with the depression or pocket 11.

Providing a seat for the tube 14 concomitantly supporting the bowl is the elongated stem generally denoted 16, preferably cast as a single member, of light metal, aluminum or the like and is provided, as illustrated, with the closely and spatially arranged ribs or fins 16 extending substantially the entire length of the stem to increase the heat radiating capacity thereof.

The seat portion 17 of the stem is enlarged and embodies fins as 18 and 19 of a diameter greater than the fins 16 but extend substantially in parallel relation therewith. Fur-

ther, seat portion 17 includes fin 20 extending radially therefrom and substantially in alignment with the longitudinal axis of the bore 21 of the stem. Interposed between the fins 18 and 20 and radially extending from the enlarged seat portion although integral therewith is the pair of spaced fins 23 and 24.

Associated with the bowl seat portion 17 is an opening 25, the sides thereof being suitably connected in air or gas tight fashion with the exterior surfaces of the tube 14, in a manner well understood in the art, but, however, in such relation that the opening of the seat is in communication with bore 15 and the channel 21 of the stem.

Spaced from the last fin 26 which is similar in all respects as the fins 16' is the annular stop flange 27 from which extends the tubular nipple 28 providing means to sustain the mouth piece or holder 29 which may be connected to the nipple in any well known manner in communicating relationship.

Preferably, the seat for the bowl, the stem, the flange and nipple thereof are cast in one piece, although, the invention is not limited in this respect as these parts may be separable and suitably fastened together.

Generally the hottest part of the bowl is along the lower faces thereof and within close proximity to the bottom wall 13. As pointed out, it is desired to disperse this heat to lower the temperature of the fumes originally developed by puffing on the holder 29 and thereby produce a cool and sweet smoke.

To this end, it is apparent that the heat on wall 13 or adjacent thereto, is conducted to the neck portion 14 and therefrom transmitted to the seat 17 and the enlarged fins as 18, 19, 20, 23 and 24. In this way, the heat at the hottest portion of the bowl is widely distributed and dispersed at its source and this action is supplemented by the radiating fins 16 of the stem, which tends to progressively and further widely distribute any heat of the fumes not diffused by the fins of the bowl seat or by the fins 12 of the bowl. Stated in another way a supplementary radiating surface is provided from the upper plane of the bowl to the remote end of the stem sustaining the holder. Thus a progressive and continuous heat radiating surfaces is provided although said surfaces are disposed on separate parts.

As many changes may be made in the above construction and many apparently widely different embodiments of the invention could be devised without departing from the scope thereof, it is intended that all matter contained in the above description or shown in the accompanying drawing shall be interpreted as illustrative and not in a limiting sense.

I claim:

1. As an article of manufacture, a bowl having an outside corrugated surface, a stem

having an outside corrugated surface, a seat provided on said stem for said bowl and in alignment therewith operative to radiate and widely distribute the heat transmitted from said bowl and away from said stem. 70

2. As an article of manufacture, a pipe including a bowl having closely spaced annular fins extending the entire height of said bowl, a stem including a seat for said bowl, said seat comprising an enlarged portion having 75 fins radiating therefrom.

3. As an article of manufacture, a pipe having a bowl embodying spaced annular fins extending the entire height thereof, an enlarged stem having a plurality of spaced fins 80 and comprising a seat for the bowl, said seat having fins juxtaposed with one portion of the bowl.

4. As an article of manufacture, a pipe having a bowl, a stem connected to the bowl, a holder sustained by said stem, a seat for the bowl at one end of the stem, the bowl, seat and stem having spaced fins, the latter being disposed continuously from the upper plane of the bowl and adjacent to a remote 90 extremity of the stem.

5. As an article of manufacture, a pipe having a bowl, a stem connected to the bowl and in communication therewith, a holder sustained by said stem, an enlarged portion 95 providing a seat for said bowl at one end of the stem, the bowl, seat and stem having closely spaced fins, the latter extending continuously from the upper plane of the bowl to one extremity of the stem. 100

6. As an article of manufacture, a pipe with a bowl having a finned surface, a stem connected to the bowl also having a finned surface, a seat for the bowl at one end of the stem having a finned surface, the fins of said seat extending laterally and radially thereof. 105

7. As an article of manufacture, a pipe with a bowl having a closely finned surface, a stem connected to the bowl also having a closely finned surface, a seat for the bowl at one end of the stem having a closely finned surface below and in alignment with the bowl, the fins of said seat extending radially, laterally and transversely thereof. 110

Signed at New York, in the county of New York and State of New York this 20 day of May 1931 A. D.
